UNITED STATES PATENT OFFICE.

ADOLPH P. GUSTAFSON, OF CHICAGO, ILLINOIS, ASSIGNOR TO M. SCHULZ COMPANY, OF CHICAGO, ILLINOIS.

SHEET-CONTROLLING MECHANISM.

Application filed May 26, 1917. Serial No. 171,109.

To all whom it may concern:

Be it known that I, ADOLPH P. GUSTAFSON, a citizen of the United States, residing at Chicago, in the county of Cook and State of Illinois, have invented a certain new and useful Improvement in Sheet-Controlling Mechanism, of which the following is a full, clear, concise, and exact description, reference being had to the accompanying drawings, forming a part of this specification.

My invention relates to sheet controlling mechanism, and especially to a form thereof in which the travelling music sheet as it progresses over the tracker board, is automatically and repeatedly restored to proper position to register the music sheet perforations with the tracker board openings.

One object of the invention is to provide a simple, practical, and effective apparatus of this kind.

Another object of the invention is to insure accuracy and reliability of operation.

Another object is to reduce the necessary work on the part of the operator, so that there can be no improper operation of the apparatus because of ignorance on the part of the operator.

In accordance with my invention I arrange to engage one of the rolls supporting the music sheet, as for example the music spool on which the music sheet is wound, so that said roll may be adjusted to effect a proper adjustment of the music sheet relatively to the tracker board to obtain proper registration of the music sheet perforations and the tracker board openings. I also arrange to automatically adjust said roll, as for example, the music spool, so that as the sheet is unwound and progresses continuously over the tracker board, said sheet will be automatically adjusted from time to time as necessary to restore it to position in which there is proper registration of music sheet and tracker board.

By thus engaging the music spool and automatically adjusting the same, instead of effecting an adjustment of the music sheet through the instrumentality of the sheet itself, I avoid all inaccuracies and improper workings due to irregularities in the sheet itself or in its edges, which irregularities are bound to occur after the sheet is used a little and its edges become slightly warped, torn or frayed. Furthermore I provide automatically for accurate adjustment in case of

sheets of different width by engaging the music roll or spool and preferably both ends of the same, so that variation in the width of the music sheet will have no effect. In the same way variations in the length of the music spool also fail to make any difference in the accuracy and effectiveness of the operation.

In the accompanying drawings Fig. 1 is an elevation of a music sheet controlling mechanism embodying my present invention:

Fig. 2 is an end elevation of the same;

Fig. 3 is a plan view of a portion of the apparatus; and

Figs. 4 and 5 are views of details of construction.

In the accompanying drawings I show a music box having side members 1 and 2 and an intervening tracker 3 supported thereby. A music spool 4 is shown above the tracker 3 and a take-up roll 5 below the same.

A rod 6 is shown mounted above the music spool 4 and having its ends slidably mounted in the uprights 1 and 2, so that said rod may slide longitudinally which is in a direction 80 lengthwise of the music spool 4. Small rods or projections 7—7 extend out laterally from said rod 6 and are provided at their outer ends with pivotally mounted lugs or fingers 8—8. The rod 6 is mounted not only for 85 slidable longitudinal movement, but also is capable of rotary movement so that the rods 7—7 may be swung down toward the music spool 4 and the fingers 8—8 permitted to engage the flanges 4^a—4^a of said spool 4. 90 The fingers 8—8 are heaviest at the outer pointed ends 8^a so that said ends 8^a tend to drop as shown in dotted lines in Fig. 1, thereby causing the pointed ends 8^a to strike the surface of the music sheet on the spool 4 first when said rod 6 is swung to move the rods or arms 7—7 toward the roll 4. The ends 8^a having struck the music spool slide outwardly on the same until they strike the spool flanges 4^a. This constitutes an engaging means for effecting an engagement with the music spool 4, and especially with the inner surfaces of the flanges 4^a thereof.

The rod 6 has its left hand end projected through the member 1 and has a connection 105 with a pin 10, as for example by having two adjustable collars 11 and 12 on the rod 6 and the pin 10 interposed between them, so that longitudinal movement on the part of the rod 6 will move the pin 10 accordingly. The 110

pin 10 is mounted on a valve 14 so that movement of the pin also moves the valve 14 and the latter is pivotally mounted upon a valve seat 15 as by means of a pivot 16 conveniently formed as an extension of the pin 10. Thus longitudinal movement on the part of the rod 6 operates the valve 14 upon the valve seat 15. The valve seat 15 is provided with three ports 17, 18 and 19 (Fig. 4) whereof the end ports 17 and 19 are connected with pneumatic tubes 20 and 22, respectively and the intermediate port with a tube 23 (Fig. 5). The tube 23 is understood to be connected with some suitable wind inducing apparatus, as for example the foot bellows, either directly or indirectly. The other tubes 20 and 22 are extended to a pair of bellows 24 and 25, respectively. The pivoted valve 14 is provided with a central slot or recess 26 by which the central port 18 may be connected with either side port 17 or 19. Thus if the port 18 is connected with the port 17 the pneumatic 24 will be collapsed and if the port 19 is connected with port 18 the pneumatic 25 will be collapsed. The pneumatics 24 and 25 are connected together by a rod 28 and the pneumatic 24 is further connected by a rod or link 29 with the lower end 30 of a slide bar 31 which is mounted above the music box top 32 and is arranged to slide longitudinally or in other words lengthwise of the tracker board and music spools. This rod 31 is provided at its other end with a downwardly extending portion 33 which engages the right hand end of the right hand music roll spindle 34. The other end 30 of said rod 31 is connected with the left hand music roll spindle 35, whereby the longitudinal movement of the rod 31 shifts the spindles 34 and 35 and thereby shifts the music spool 4 in a longitudinal direction. The rod 31 being connected by link 29 with the two bellows 24 and 25, it is obvious that the collapse of either one or the other of these two bellows will cause a movement in one direction or the other of the rod 31 and therefore of the music spool 4. Thus it will be seen that the collapse of either one or the other of said bellows 24 and 25 causes a shifting movement in one direction or the other of said spool 4, and it will further be seen that the collapse of one or the other of said bellows and the consequent shifting movement of the music spool will be caused by an adjustment of the pivoted valve 14 and this in turn will be caused by the longitudinal movement in one direction or the other of the slide rod 6. The arrangement is such that a movement of the slide rod 6 in one direction will cause an adjustment of the music spool 4 in the opposite direction. Thus when the fingers 8-8 are in engagement with the flanges 4^a of the music spool 4 and said music spool 4 becomes shifted to one side or the other so

as to derange the music sheet and place it out of proper position relatively to the tracker board, such movement of the music spool will by reason of the intervening mechanism cause an actuation of the valve 14 and bellows 24 and result in the latter moving said music spool back to its original or normal position, and thereby restoring the music sheet to proper registering position with the tracker board. 75

It will be seen that the fingers 8-8 when coming into contact with the music spool 4 and the flanges 4^a thereof will automatically cause an adjustment of the rod 6 and spool 4 by the establishment of an equilibrium between the pivoted fingers 8-8 and the music spool flanges 4^a. In other words, if the music spool 4 is substantially to one side of its proper position one of the fingers 8 will act against its flange 4^a before the other finger 8 comes in contact with its flange, the result of which will be that the first mentioned finger will push the music spool longitudinally in a direction to bring the other flange in contact with the other finger 8, whereby the music spool is adjusted until both fingers 8 contact with the flanges 4^a and are at the same inclination so that each finger pushes against its flange with the same force. 80 85

As an arrangement for automatically engaging the spool engaging means with the spool and disengaging the same therefrom, I show an arrangement by which the rod 6 may be turned automatically by pneumatic means so as to swing the arms 7-7 toward the spool 4 when the instrument starts to play and retains it there during the playing, and also by which said arms 7 are swung upwardly and away from the spool 4 when the playing stops or when reroiling is taking place. In such arrangement an operating pneumatic 37 (Fig. 5) is shown having its swinging leaf 38 provided with an arm or rod 39, and this arm 39 is arranged to engage an arm 40 on the rod 6. Thus when the pneumatic 37 is expanded the arm 39 rests upon the arm 40 and by the aid of a spring 45 (Fig. 2) pushes the arm 40 downwardly so as to cause the arms 7 of the rod 6 to swing upwardly and move the fingers 8 away from the music spool 4. Thus when there is no pressure on the pneumatic 37, as for example during reroiling or when the instrument is not playing, said pneumatic 37 will be expanded and the music roll engaging means will be out of engagement with the music roll. When, however, said pneumatic 37 is collapsed, the arm 39 swings upwardly, thereby releasing the arm 40 on the rod 6 and permitting the weight of the fingers 8 and arms 7 to swing said rod 6 downwardly so as to cause the fingers 8 to engage with the music roll flanges. Thus when the instrument starts to play the pneu- 100 105 110 115 120 125

matic 37 immediately collapses and the fingers 8 automatically descend and engage the music spool and, as previously explained, these fingers slide the spool in one way or 5 the other until it is properly centered with its flanges engaged by the same holding pressure of the two fingers 8, the pneumatic 37 being connected by a tube 47 with the wind inducing apparatus. When in such 10 engagement the automatic adjustment of the music spool longitudinally of the spool or in other words crosswise of the direction of the travel of the music sheet will take place so as to automatically restore the music sheet 15 to its proper tracking position relatively to the openings of the tracker board. As previously explained this automatic adjustment or restoring action will be reliable and accurate because of its being effected through 20 the medium of the music spool and its flanges, instead of by means of the music sheet itself, the latter being very irregular and varying in its width even when new, but very soon becoming bent, crumpled and 25 torn, so that reliability and accuracy is out of the question.

The tube 23 running to the valve seat 15 is connected to pneumatic 37, and is thus connected with the wind inducing apparatus 30 through the same.

In my Patent No. 1,313,226, August 12, 1919, tracking devices for automatic musical instruments, application for reissue of which is now pending in the Patent Office, 35 I have disclosed and claimed a sheet controlling mechanism having certain features of the mechanism herein set forth and hence certain features of the mechanism hereof are not claimed herein.

40 It will be understood that changes and modifications may be made without departing from the spirit of the invention.

What I claim is:

1. The combination with the tracker, 45 music spool and means for supporting said spool, of means for automatically engaging and disengaging said spool, and mechanism for continuously effecting an automatic relative adjustment between said spool and 50 tracker for trackage purposes during the playing operation.

2. The combination with the tracker, 55 music roll and means for supporting said roll, of means for automatically engaging and disengaging the roll, and means for effecting a continuous automatic adjustment of said roll engaging means to secure a continuous trackage adjustment of the music sheet.

60 3. The combination with the tracker, music roll and means for supporting said roll, of swinging means arranged for swinging movement toward and away from the roll to become engaged with and disengaged 65 from the same, means whereby said swing-

ing means may be automatically swung to permit engagement with and disengagement from said roll, and mechanism for effecting a continuous automatic adjustment of said swinging means in a direction lengthwise 70 of the roll and relatively to the tracker so as to secure automatic trackage adjustment.

4. The combination with the tracker and rolls supporting the music sheet, of means for engaging the flanges of one of said rolls 75 and pneumatic mechanism operable by said flange engaging means for effecting a relative adjustment between the music sheet and the tracker.

5. The combination with the tracker and 80 the music spool and take-up roll, of means for engaging the flanges of the music spool and mechanism operable by said means for effecting a relative adjustment of the music sheet and tracker in a direction transverse 85 to the direction of movement of the music sheet.

6. The combination with the tracker, the music spool and take-up roll, of a pair of 90 arms provided with pivotally mounted fingers, means for supporting said arms and adjusting them so as to engage the flanges of the music spool and pneumatic mechanism operable by said arm supporting means for effecting a relative adjustment of tracker 95 and music sheet.

7. The combination with the tracker, the music spool and take-up roll, of a longitudinally slidable bar provided with projecting arms carrying pivotally mounted fingers, 100 valve mechanism connected with and operated by said bar and pneumatics connected with and operated by said valve mechanism.

8. The combination with the tracker, the music spool and take-up roll, of a longitudinally slidable bar provided with projecting arms carrying pivotally mounted fingers, 105 valve mechanism connected with and operated by said bar, pneumatics connected with and operated by said valve mechanism, 110 and means operated by said pneumatics for effecting a relative adjustment between tracker and music sheet.

9. The combination with the tracker, the music spool, and take-up roll, of a longitudinally slidable bar provided with projecting arms carrying pivotally mounted fingers, 115 valve mechanism connected with and operated by said bar, pneumatics connected with and operated by said valve mechanism, 120 registering mechanism operated by said pneumatics, and supplemental pneumatic means for automatically adjusting said bar so as to cause it to engage and disengage the music spool flanges.

10. The combination with the tracker, the music spool, and take-up roll, of a longitudinally slidable bar provided with projecting arms carrying pivotally mounted fingers, 125 valve mechanism connected with and oper-

- ated by said bar, pneumatics connected with and operated by said valve mechanism, means operated by said pneumatics for effecting a relative adjustment between the 5 tracker and music sheet, and supplemental pneumatic means for automatically adjusting said bar so as to cause it to engage and disengage the music spool flanges, said supplemental pneumatic means being operable 10 to cause the engagement of the music spool during the playing operation and the disengaging of the same when the playing is discontinued.
11. The combination with the tracker and 15 rolls for the music sheet, of means for engaging one of said rolls, said means being movable toward and away from the roll to permit engagement therewith and disengagement therefrom, means for automatically effecting 20 engaging and disengaging movements of said means, said engaging means being adjustable longitudinally of said roll and means for effecting a longitudinal adjust-

ment of said means while said means are in engagement with the roll.

12. The combination with the tracker and rolls of the music sheet, of means for engaging one of said rolls, said means being movable toward and away from the roll to permit engagement therewith and disengagement 30 therefrom, means for automatically effecting engaging and disengaging movements of said means, said engaging means being adjustable longitudinally of said roll and means for effecting a longitudinal adjust- 35 ment of said means while said means are in engagement with said roll, said adjusting means being operable by the longitudinal movement of said roll engaging means.

In witness whereof, I hereunto subscribe my name this 27th day of April, A. D., 1917.

ADOLPH P. GUSTAFSON.
